WIRELESS REMOTE CONTROL SYSTEM

BACKGROUND OF THE INVENTION

As is well known to those versed in the art, remote control systems are subject to certain problems which have not heretofore been satisfactorily overcome, including that of fail-safe operation, and low power requirements at the remote station.

SUMMARY

Accordingly, it is an important object of the present invention to provide a wireless remote control system which obviates the above-mentioned difficulties, effectively achieving continuous operation of the operating station as required, upon intermittent operation of the signal station so that relatively small power is required by the signaling station.

It is still another object of the present invention to provide a wireless remote control system having the advantageous characteristics mentioned in the preceding paragraph, which can be used over any desired distance, the operating station being placed in operation immediately upon the receipt of a signal from the signaling station and operates for a predetermined period of time after which operation ceases in the absence of a signal from the signaling station and wherein the operating station terminates its operation upon the existence of a fault.

Other objects of the present invention will become apparent upon reading the following specification and referring to the accompanying drawing, which form a material part of this disclosure.

The invention accordingly consists in the features of construction, combinations of elements, and arrangements of parts, which will be exemplified in the construction hereinafter described, and of which the scope will be indicated by the appended claims.

BRIEF DESCRIPTION OF THE DRAWING

FIG. 1 is a schematic representation of a signaling station in accordance with the teachings of the present invention; and

FIG. 1a is a continuation of the schematic of FIG. 1 and represents the operating station of the present invention

DESCRIPTION OF THE PREFERRED EMBODIMENT

Referring initially to FIG. 1a the operating station is connected to a B+ or power source by a conductor 50, the other side of the power source being connected to ground at 51. A rectifier is generally designated 2, and is advantageously a silicon controlled rectifier including an anode 1, cathode 3 and gate 5, the rectifier anode 1 being connected by the conductor 50 to B+. By the nature of rectifier 2, any loads connected between the rectifier cathode 3 and ground will only be energized when a positive pulse is applied to the gate 5.

A conductor 52 is connected from the rectifier cathode 3 to an interval timer circuit, generally designated 8, which is grounded at 4. In addition, a control device circuit is generally designated 53 and connected to the conductor 52 and also to ground at 54. Thus, the timer circuit 8 and control circuit 53 provide loads connected between the rectifier cathode 3 and the ground, which loads will be energized from B+ upon triggering of the rectifier 2 by a positive pulse at gate 5. The loads 8 and 53 remain energized until the rectifier 2 is turned off.

The control device circuit 53 may include a relay coil 6, connected in parallel with a resistance 7. The parallel connected coil 6 and resistance 7 may be connected by a conductor 9 through the conductor 52 to rectifier cathode 3. Relay contacts or switch means are generally designated 10, and connected to a system to be controlled. Thus, the control circuit 53 is connected between rectifier cathode 3 and ground 54 and will operate upon triggering of the rectifier, until the rectifier is turned off. The parallelly connected resistor 7 is provided to assure that sufficient current passes through the rectifier 2 in order to maintain its conductance once it has been fired.

The interval timer circuit 8, also connected between rectifier cathode 3 and ground 4 is of the unijunction transistor timing circuit type. The circuit 8 includes a series connected resistance 17 and capacitance 18 connected together by a conductor 19, with the resistance 17 connected by a conductor 55 to conductor 52, and capacitor 18 connected by a conductor 20 to the ground 4. Also included in the interval timer circuit is a series connected capacitance-resistance circuit including a capacitance 11 connected by a conductor 25 to a resistor 16, 10 the capacitor being connected by a conductor 24 to the conductor 52, and the resistor 16 being connected by a conductor 56 to ground 4. Thus, the resistance-capacitor circuit 17, 18 may be considered as in parallel with the capacitor-resistance circuit 11, 16, both being connected between rectifier cathode 3 and ground.

The interval timer circuit 8 includes a transistor 21 having an emitter 57, a base₁ 15 and a base₂ 23. The emitter 57 is connected to the conductor 19 at a juncture 14 between the resistor 17 and capacitor 18. The base₁ 15 is connected to the conductor 25 at a juncture 58 between the capacitance 11 and resistance 16, and the base₂ 23 is connected through a resistor 22 to the conductor 24 for connection to the rectifier cathode 3.

In addition, a diode 12 has its anode connected by a conductor 13 to the juncture 14 between resistance 17 and the capacitance 18. The cathode of the diode 12 is connected by a conductor 40 to a receiver output which becomes ground when the receiver output relay is energized.

A conductor 60 is connected to receiver output and becomes plus when the receiver output is energized, being connected through a parallel capacitance-resistance circuit 30 and conductor 61 to the gate 5 of rectifier 2. The circuit 30 includes a capacitance 32 connected in parallel with the resistance 31 to protect the rectifier 2 from a continuous high value of direct current.

The interval timing circuit 8 generates a positive pulse between its base₁ terminal 15 and ground 4, across the resistor 16. One basic timing element of the circuit 8 is the resistor 17 connected between the rectifier cathode 3 and emitter 57 of the transistor 21. The other basic timing element of the circuit 8 is the capacitance 18 with its positive lead 19 connected to the transistor emitter 57 and its negative lead connected to the ground. This provides a series circuit from the rectifier cathode 3 with the resistance 17 and capacitance 18, which is grounded at its negative lead 20. Upon firing or triggering of the rectifier 2, the voltage at the emitter 57 of the transistor 21 begins to build up according to the resistance-capacitance time constant curve of the components 17 and 18. When the emitter 57 reaches a certain voltage level, the transistor 21 will conduct in the emitter to base₁. Thus, the time required to fire the transistor 21 is a function of the resistance-capacitance circuit 17, 18, so that these values may be selected to achieve the desired period.

The resistor 16 of the capacitance-resistance circuit 11, 16 is connected to ground, and when the transistor 21 conducts, the capacitance 18 will be connected through the base, across the resistance 16 causing the capacitor 18 to discharge. This discharge is the output pulse of the interval timing circuit 8. 60 When the capacitor 18 discharges, the emitter voltage is reduced below its firing level, so that the transistor conduction through base, terminates. Providing voltage is present for the interval timing circuit operation, the timing cycle and its completion pulse will occur repeatedly.

The timing circuit 8 also includes a resistor 22 connected between the rectifier cathode 3 and base₂ of transistor 21. This resistor 22 protects the transistor 21 from excessive current and acts as a temperature compensating element. Its value is chosen in accordance with safe current limits to achieve the greatest degree of timing accuracy over a given operation temperature range.

In practice, the interval timing circuit 8 may be set for a minute or more. The capacitance-resistance circuit 11, 16 is selected to build up to full supply voltage immediately, say in one second or less. This series connected capacitance-re-

sistance circuit 11,16 will charge the capacitor 11 to the supply voltage almost immediately. At the end of the selected timing interval of circuit 8, a pulse will appear across the resistor 16, which acts as a voltage in "series-aiding" with the voltage stored in the capacitor 11, which capacitor voltage is substantially equal to the supply voltage. Therefore, momentarily, there will be a voltage present at the cathode 3 of rectifier 2, from the positive side of capacitor 11, which is more positive than the supply voltage, therefore serving to turn off the rectifier 2 and deenergize the control circuit 53.

It will now be understood that the control circuit 53 can be energized by a low power pulse to the gate 5 of rectifier 2, and once the control circuit 53 has been energized the natural holding action of the rectifier 2 will maintain the circuit 53 in energized condition. However, the voltage applied to the circuit 53 is also applied to the timing circuit 8, and after a predetermined interval the timing circuit will fire and add a positive pulse voltage to the voltage stored in capacitor 11 to momentarily raise the voltage of the rectifier cathode 3 above that of the power supply. This turns off the rectifier 2 and the control circuit 53 and timing circuit 8 itself.

As noted hereinbefore, the rectifier gate 5 is energized by a pulse from the receiver output through conductor 60 and capacitance-resistance parallel circuit 30, the latter reducing the value of direct current to prevent damage to the rectifier.

The other receiver output is connected to conductor 40 and is automatically grounded upon reception of a signal. The diode 12 connected to conductor 40 effectively protects the transistor 21 from positive potential in the receiver. When the cathode of diode 12 become grounded, the capacitance 18 is discharged, which action causes the timing circuit 8 to reset to zero time. As the transmitter transmits pulses at intervals slightly shorter than the time set at the interval timer 8, the interval timer will keep being reset to zero time before the interval expires, so that the control relay 6 will not be deenergized so long as a transmitted pulse is received.

Considering now the signaling station of FIG. 1, there are a pair of conductors or leads 65 and 66 connected across a low impedance sensor or actuator, the conductor 65 being connected to any power supply 64 which may be a battery or ordinary house current. In this way, the sensor serves as a main power switch, being interposed between the power supply 64 and the remainder of the circuit. That is, a demand for operation at the operating station is made by lowered or decreased impedance of the sensor, to effectively connect the signaling station to its relatively small power source 64.

It will be appreciated that in one embodiment of this invention the sensor or control device may advantageously be any of a variety of thermostatically actuated switches.

The conductor 66 is connected to a periodic verification timer or cycle timer generally designated 67 which is connected to ground, as at 68. The periodic verification timer 67 includes a resistance-capacitance circuit constituted of resistance 69 connected by conductor 70 in series with capacitance 71, the resistance being connected to conductor 66 and the capacitance to ground 68. A transistor 72 includes an emitter 73 connected at a juncture 74 to the conductor 70 between resistance 69 and capacitance 71. A base₁ 75 is connected by a conductor 76 through a resistance 77 to ground 68, and base₂ 78 of transistor 72 is connected by a resistance 79 to conductor 66.

A rectifier 80 includes an anode 81 connected by a conductor 82 to the conductor 66, and includes a cathode 83 and a gate 84. The gate is connected to the base₁ of transistor 72 by a conductor 85 through a capacitance-resistance circuit 86 including a capacitance 87 and resistance 88 parallelly connected.

The rectifier 80, which may be a silicon controlled rectifier, has its cathode 83 connected by a conductor 90 to an interval timer circuit generally designated 91. In addition, the cathode 83 of rectifier 80 is also connected to a transmitter 92, as by a conductor 93 connected to conductor 90. The timer circuit 91 is connected between the rectifier cathode 83 and ground 94,

and the transmitter 92 is connected between the rectifier cathode 83 and ground at 115.

The interval timer 91 may be of substantially the same circuitry as the interval timer 8 described hereinbefore, with components selected to achieve the desired interval of time. The circuit 91 includes: a series connected resistance 95 and capacitance 96, the resistance being connected by conductor 97 through conductor 90 to the rectifier cathode 83, and the capacitance being connected through conductor 98 to ground 94; a series connected capacitance-resistance circuit including a capacitance 99 and resistance 100, the capacitance being connected by a conductor 101 to conductor 90 and thence to rectifier cathode 83, and the resistance 100 being connected through conductor 102 to ground 94; a transistor 103 including an emitter 104 connected at juncture 105 between the series connected resistance 95 and capacitance 96. The transistor 103 includes a base₁ 106 connected to a juncture 107 between the series connected capacitance 99 and resistance 100. The transistor 103 also includes a base₂ 108 connected through a resistance 109 to the conductor 101, and thereby to the cathode 83 of rectifier 80.

In operation, actuation of a sensor to lower the impedance thereof places the timer circuit 67 on line to the power source 64. This is a very low drain circuit, measured in thousandths of an ampere, and after a predetermined interval of time, a positive pulse that is developed across the base₁ resistor 77 is applied through circuit 86 to rectifier gate 84, causing the rectifier to conduct. Thus, a delay of predetermined interval at very low current drainage is required between actuation of a sensor and triggering of the rectifier 80. This timer circuit 67 is set for a relatively long period, say more than 15 seconds.

Immediately upon conductance or triggering of the rectifier 80, the interval timer 91 and transmitter 92 are both established as loads on the power supply. The transmitter commences to transmit a coded signal for reception by the above-described operating station.

The interval timer circuit 91 operates in the manner described hereinbefore, for a very short duration, say less than 5 seconds, after which it transmits a positive pulse to the cathode 83 of rectifier 80 greater than that of the power supplied to effect cessation of conduction through the rectifier.

Should the demand continue to exist, the timer circuit 67 will once again repeat its timing cycle, at the end of which will be triggered the rectifier 80, to cause operation of the timer circuit 91 and transmitter 92. Thus it will be seen that the transmitter is caused to operate over relatively short periods determined by the timer circuit 91, which operating periods are spaced apart by relatively long periods determined by the operating constants of circuit 67. This serves to minimize the power drain at the signaling station; and, as discussed hereinbefore, permits continuous operation at the operating station.

It will also be understood, in the signaling circuit of this invention, that the control device or sensor need only arrive at some minimal resistance value in order to operate the timer circuit 67. As the latter represents a relatively high impedance, the relatively low impedance of the sensor will have little effect on timer operation. However, a lower voltage for the timer will tend to increase its timing interval, which is advantageous in that more time will be allowed for the sensor to further reduce its impedance before the transmitter is energized. Since power is supplied to the transmitter through the impedance of the sensor, the sensor's impedance should be low in order to achieve maximum transmitted power.

While the device of this invention has been primarily developed and employed for use in remotely controlled temperature control apparatus, it is appreciated that the device of this invention is capable of many varied applications, all of which are intended to be comprehended herein.

From the foregoing, it is seen that the wireless remote control system of this output fully accomplishes its intended objects and is well adapted to meet practical conditions of manufacture, installation and use.

Although the present invention has been described in some detail by way of illustration and example for purposes of clarity of understanding, it is understood that certain changes and modifications may be made within the spirit of the invention and scope of the appended claims.

We claim:

1. In a wireless remote control system, a signal station comprising: a sensor; a first power source connected to the sensor; a first rectifier having an anode, cathode and gate with its anode connected to the sensor for receiving power through the latter; a cycle timer having a relatively long repetition connected to the sensors and gate and operative only during actuation of the sensor to periodically trigger the gate; a transmitter connected to the cathode of the rectifier for operation upon triggering of the rectifier; and an interval timer connected to the rectifier cathode and transmitter for operation upon triggering of the rectifier, for terminating rectifier and transmitter operation after a relatively short period; whereby a series of intermittent signals are transmitted by the transmitter during the actuation of the sensor.

2. A wireless remote control system according to claim 1, said rectifier comprising a silicon controlled rectifier, and a protective resistance-capacitance circuit interposed between said cycle timer and silicon controlled rectifier.

3. A wireless remote control system according to claim 1, said interval timer comprising a unijunction transistor timing circuit.

4. A wireless remote control system according to claim 3, said unijunction transistor timing circuit comprising a series connected resistance-capacitance circuit having its resistance connected to said rectifier cathode and its capacitance connected to ground; a series connected capacitance-resistance circuit having its capacitance connected to said rectifier cathode and its resistance connected to ground; a transistor having an emitter, a base₁ and a base₂, with its emitter connected to said resistance-capacitance circuit between resistance and capacitance thereof; the base₁ being connected to the capacitance-resistance circuit between its capacitance and resistance; and an additional resistance connected between the base₂ and said rectifier cathode.

5. A wireless remote control system according to claim 1, in combination with a receiver for receiving transmitted signals; a second power source; a second rectifier having an anode, cathode and gate with its anode connected to said second power source and its gate connected to said receiver for triggering said second rectifier responsive to received signal; a control device connected to said second rectifier cathode for energizing a system to be controlled upon triggering of said second rectifier; and a second interval timer connected to said second rectifier cathode and control device for terminating operation of said second rectifier after predetermined period in the absence of a transmitted signal during the predetermined period.

6. A wireless remote control system according to claim 5, said second interval timer comprising a unijunction transistor timing circuit.

7. A wireless remote control system according to claim 6, said unijunction transistor timing circuit comprising a series connected resistance-capacitance circuit having its resistance connected to said second rectifier cathode and its capacitance connected to ground; a series connected capacitance-resistance circuit having its capacitance connected to said second rectifier cathode and its resistance connected to ground; a transistor having an emitter, a base₁ and a base₂, with its emitter connected to said resistance-capacitance circuit between the resistance and capacitance thereof; the base₁ being connected to said capacitance-resistance circuit between the capacitance and resistance thereof; and a resistance connected between the base₂ and said second rectifier cathode.

8. A wireless remote control system according to claim 7 in combination with a third rectifier having an anode and cathode with its anode connected to said emitter and its cathode switchable to ground.

9. A wireless remote control system according to claim 5, in combination with a parallel resistance-capacitance circuit connected between said receiver and gate to minimize direct current.

10. A timer circuit for controlling a rectifier; comprising a series connected resistance-capacitance circuit having the resistance connected to the rectifier cathode and the capacitance connected to ground; a series connected capacitance-resistance circuit having its capacitance connected to the rectifier cathode and its resistance connected to ground; a transistor having an emitter, a base₁ and a base₂, with its emitter connected to the resistance-capacitance circuit between the resistance and capacitance thereof; base₁ being connected to said capacitance-resistance circuit between the capacitance and resistance thereof; a resistance connected between the base₂ and rectifier cathode; a power supply means coupled between the rectifier anode and cathode; and triggering means coupled to the gate of the rectifier.

11. An operating station for a wireless remote control system comprising a receiver for receiving remotely transmitted signals; a power source; a rectifier having an anode, cathode and gate with its anode connected to said power source and its gate connected to said receiver for triggering the rectifier responsive to received signals; a control means connected to the rectifier cathode for energizing a system to be controlled upon triggering of the rectifier; and an interval timer means connected to said rectifier cathode and said control means for automatically terminating rectifier operation after a predetermined period in the absence of a transmitted signal during the predetermined period.

12. An operating station for a wireless remote control system comprising a receiver for receiving remotely transmitted signals; a power source; a rectifier having an anode, cathode and gate with its anode connected to said power source and its gate connected to said receiver for triggering the rectifier responsive to received signals; a control device connected to the rectifier cathode for energizing a system to be controlled upon triggering of the rectifier; and an interval timer connected to said rectifier cathode and control device for terminating rectifier operation after a predetermined period in the absence of a transmitted signal during the predetermined period, said interval timer comprising a series connected resistance-capacitance circuit having its resistance connected to the rectifier cathode and its capacitance connected to the ground; a series connected capacitance-resistance circuit having its capacitance connected to the rectifier cathode and its resistance connected to ground; a transistor having an emitter, a base₁ and a base₂, with its emitter connected to the resistance-capacitance circuit between the resistance and capacitance thereof; the base₁ being connected to said capacitance-resistance circuit between the capacitance and resistance thereof; and a resistor connected between the base₂ and rectifier cathode.

13. An operating station according to claim 12, in combination with an additional rectifier having an anode and cathode with its anode connected to said emitter and its cathode connected to ground.

14. A wireless remote control system comprising a sensing and signaling station and a remotely disposed operation station: said sensing and signaling station comprising electronic sensing means; a source of potential; a transmitter and transmitter actuation means; said electronic sensing means upon detection of a predetermined condition being operative to connect said source of potential to said transmitter actuation means to activate the same; said transmitter actuation means including a switch means coupled to said transmitter to connect said source of potential thereto, and a first delay means to delay actuation of said switch means for a predetermined interval of time after the initial sensing of said predetermined condition by electronic sensing means; said transmitter, upon

65
70
75

75

activation thereof, generating a signal transmission therefrom; said sensing and signaling station further comprising a second delay means connected to said switch means, said second delay means being operative to inhibit said switch means a predetermined time after activation of said switch means by said first delay means to thereby deactivate said transmitter;

said remotely disposed operating station comprising a receiver and an output device, said receiver being adapted to receive the signal transmission from said transmitter, means connecting the output of said receiver to said output device, and said receiver being operative upon reception of said signal transmission to couple a signal to said output device to activate the same.

15. A wireless remote control system in accordance with claim 14, wherein said second delay means is activated to commence its timing operation by said switch means when said switch means is activated.

16. A wireless remote control system in accordance with claim 15, wherein the time delay of said second delay means is shorter than the time delay of said first delay means.

17. A wireless remote control system in accordance with claim 16, wherein said source of potential is a battery.

18. A wireless remote control system in accordance with claim 15, wherein:

said receiver includes output means for coupling the output thereof to the output device; and
said output means being operable to maintain said output device in an activated condition for a predetermined period of time.

19. A wireless remote control system in accordance with claim 18, wherein said output means includes third delay means, said third delay means being operable to inactivate said output device a predetermined interval of time after activation of said output device in the absence of a transmitted signal during said predetermined interval of time.

20. A wireless remote control system in accordance with claim 19, wherein said output means includes second switch means. Said second switch means being operative to actuate and maintain said output device in an actuated state.

21. A wireless remote control system in accordance with claim 20, wherein said third delay means is connected to said second switch means, and said third delay means being operative to inhibit said second switch means a predetermined interval of time after activation of said second switch means to thereby deactivate said output device in the absence of a transmitted signal during said predetermined interval of time.

22. A wireless remote control system in accordance with claim 21, wherein said third delay means is activated to commence its timing operation by said second switch means when said second switch means is activated.

23. A wireless remote control system in accordance with claim 22 wherein the time delay of said third delay means is longer than the time delay of said first and second delay means.

24. A wireless remote control system in accordance with claim 23, wherein said switch means comprises a silicon controlled rectifier.

25. A wireless remote control system in accordance with

claim 24, wherein said first time delay means comprises: a first unijunction transistor having an emitter, a first base and a second base;

a first resistor and a first capacitor serially connected between one terminal of said electronic sensing means and a ground terminal, the junction between said first resistor and said first capacitor being connected to said emitter;

first resistive means interconnected between said one terminal of said electronic sensing means and said second base;

second resistive means interconnecting said first base and ground; and

coupling means connecting said first base to said silicon controlled rectifier.

26. A wireless remote control system in accordance with claim 25, wherein, said second delay means comprises:

a second unijunction transistor having an emitter, a first base and a second base;

a second resistor and a second capacitor serially connected between said silicon controlled rectifier and a ground terminal, the junction between said second resistor and said second capacitor being connected to said emitter of said second unijunction transistor;

a third capacitor and a third resistor serially connected between said silicon controlled rectifier and said ground terminal, the junction between said third capacitor and said third resistor being connected to said first base of said second unijunction transistor, and

third resistive means interconnecting said second base of said second unijunction transistor and said silicon controlled rectifier.

27. A wireless remote control system in accordance with claim 26, wherein said second switch means comprises a second silicon controlled rectifier.

28. A wireless remote control system in accordance with claim 26, wherein said third delay means comprises:

a third unijunction transistor having an emitter, a first base, and a second base;

a fourth resistor and a fourth capacitor serially connected between said second silicon controlled rectifier and a ground terminal, the junction between said fourth resistor and said fourth capacitor being connected to said emitter of said third unijunction transistor;

a fifth capacitor and a fifth resistor serially connected between said second silicon controlled rectifier and said ground terminal, the junction between said fifth capacitor and said fifth resistor being connected to said first base of said third unijunction transistor; and

fourth resistive means interconnecting said second base of said third unijunction transistor and said second silicon controlled rectifier.

29. A wireless remote control system in accordance with claim 28 wherein said output means includes relay means interconnected between said silicon controlled rectifier and said output device, said relay device being operative to maintain said output device in an actuated condition when said silicon controlled rectifier is maintained in an activated condition.
